UNITED STATES PATENT OFFICE.

SAMUEL BUFFIN, OF ANDERSON, INDIANA.

STRAW-STACKER.

SPECIFICATION forming part of Letters Patent No. 427,736, dated May 13, 1890.

Application filed November 6, 1889. Serial No. 329,387. (No model.)

To all whom it may concern:

Be it known that I, SAMUEL BUFFIN, a citizen of the United States, residing at Anderson, in the county of Madison and State of Indiana, have invented certain new and useful Improvements in Straw-Stackers; and I do hereby declare the following to be a full, clear, and exact description of the invention, such as will enable others skilled in the art 10 to which it appertains to make and use the same.

My invention relates to improvements in straw-stackers, and more particularly to improvements in the mechanism employed in 15 raising and lowering the carrier-frame and for swinging the same from side to side automatically.

My said invention consists in certain novelties in the details of the construction, arrangement, and combination of the various parts, all of which I will now proceed to point out and describe, reference being had to the accompanying drawings, in which—

Figure 1 is a perspective of a straw-stacker 25 embodying my said invention, showing the elevator-frame unfolded and in an inoperative position. Fig. 2 is a side elevation of the same, showing the machine in an operative position and ready for transportation. Fig. 30 3 is a side elevation of the opposite from that shown in Fig. 2, parts of the same being broken away. Fig. 4 is an end elevation, parts of the machine being removed. Fig. 5 is a top plan view of the turn-table, the elevator-frame being removed and one of the switch 35 or end pieces of the rack also being removed. Fig. 6 is a bottom plan view of a portion of the main frame of the machine and the turn-table supported thereon. Fig. 7 is a bottom 40 plan view of the turn-table and the pinion engaging the rack of said table, the swinging arm or bracket on which said pinion is supported being shown in dotted lines. Figs. 8, 9, 10, 11, 12, 13, and 14 are details illustrating 45 various parts of my said invention.

Referring to said drawings, 1 represents the truck or main frame of the stacker, consisting of the side bars 2 and transverse bars 3, forming a substantially square space between said side and transverse bars. To the ends of the frame are secured suitable axles

4, upon which are mounted wheels 5. In the corners of the space formed between the side and transverse bars are secured diagonal brackets 6, said brackets forming braces for 55 the frame. To each bracket is secured a pintle 7, on which is mounted a roller-bearing 8.

9 is a circular turn-table provided with a central hub 10 and diametrically-arranged 60 braces or arms 11, connecting the hub and table. The under side of the turn-table is provided with an inwardly-projecting annular flange 12, the bottom of which rests upon the roller-bearings 8. 65

14 are upwardly-projecting studs formed on the brackets 6, having projecting pintles 15, on which are mounted rollers 16, which engage the upper surface of the annular flange 12 and serve to hold the table in position 70 upon its bearings.

15 is the elevator-frame, which may be of any desired construction, and is provided with the hinged and folding section 16.

17 is a transverse shaft mounted in bearings in the lower rear end of the elevator-frame. Said shaft projects beyond the sides of the frame, and to its ends are pivotally secured lever-arms 18, extending parallel with each other and having their opposite ends 80 pivotally secured to diametrically-opposite points on the outside of the turn-table. Said lever-arms are preferably formed in the shape of a truss-brace and are provided with the brace-bars 19. 85

20 are parallel projecting arms secured to the turn-table.

21 are upwardly-extending and parallel segmental racks rigidly secured to said arms and to the turn-table. 90

22 are downwardly-extending and parallel segmental racks rigidly secured to the lower rear end of the elevator-frame. Said segmental racks 21 and 22 are arranged upon the arcs of circles having different centers, 95 the racks 22 being larger than the racks 21 and formed in the arc of a circle of greater diameter than the circle in the arc of which the rack 21 is formed. Said racks 22 pass on the outside of the racks 21 and slightly overlap the same. The lever-arms are so arranged that their ends are pivoted at the cen- 100

ters of the circles in the arcs of which the racks are formed.

23 are bearings formed in the lever-arms 18, and preferably in the cross bars or braces 19, 5 as shown.

24 is a transverse counter-shaft mounted in the bearings 23.

25 are pinions rigidly mounted upon the shaft 24 and engaging with the segmental 10 racks 22.

26 are smaller pinions, also rigidly mounted upon the shaft 24 and adapted to engage with the segmental racks 21.

27 is a worm-wheel rigidly mounted on the 15 shaft 24 at its center. Said worm-wheel is inclosed by a box or housing 28, loosely mounted on said shaft 24 and formed in upper and lower sections bolted to each other. The upper section of the box or housing has 20 projecting therefrom a sleeve-bearing 29, which terminates in a forked end 30.

31 are bearings formed in the end of each arm of the fork.

32 is a short shaft mounted in the sleeve-bearing 29, said shaft being arranged substantially at right angles to the shaft 24.

33 is a worm formed on one end of the shaft 32 and engaging with the worm-wheel 27, said worm being located within the box 30 or housing.

34 is a bevel-gear rigidly mounted on the outer end of the shaft and located between the arms of the fork 30.

35 are bearings formed on the lever-arms 35 near their lower pivoted ends.

36 is a main shaft mounted in said bearings 35 and passing through the bearings 31 in the forked end of the sleeve.

37 is a bevel-gear mounted on the shaft 36 40 between the forked end of said sleeve and engaging with the bevel-gear 34.

38 is a crank secured to one end of the shaft

36. If desired, each end of the shaft may be provided with a crank. The outer ends of 45 the arms 20 project beyond the frames of the racks 21 and form stops 39. To one side of the racks 21, at the point where the teeth terminate, I provide teeth or projections 40.

41 are cams rigidly mounted on the shaft 50 24 next to and on the inside of the pinions 26. Said cams are provided with shoulders 42, which as the shaft is revolved are adapted to engage with the teeth or projections 40 and throw the pinions 26 in gear with the racks 21.

55 The construction so far described constitutes the mechanism by means of which the front and rear ends of the elevator-frame may be simultaneously raised or lowered. For convenience I will now describe the operation of this part of my said invention. When 60 the stacker is in an inoperative position and ready for transportation and the hinged section of the elevator-frame is folded up, as shown in Fig. 2, the pinions 26 are disengaged from the racks 21 and the center of gravity of the machine is back of the pivotal

points of the lower ends of the lever-arms. The cams 41 then rest upon the stops 40, thus limiting the further downward movement of the rear end of the elevator-frame, the forward end of said frame resting upon supports 44, secured to the forward end of the truck on which said elevator-frame is mounted. When it is desired to use the stacker, the elevator-frame is unfolded, as shown in Fig. 1, the center of gravity of said elevator-frame changes to the opposite side of the lower pivoted ends of the lever-arms from that shown in Fig. 2, and the rear end of the elevator-frame rises until the cams 41 rest against the under side of the 70 teeth or projections 40. As the shaft 24 is rotated through the mechanism described, the shoulders 42 engage with the stops 40 and throw the pinions 26 in gear with the racks 21. As said shaft is rotated, the pinions 25, 75 engaging with the racks 22, raise the forward end of the elevator-frame. At the same time the pinions 26 engage with the racks 21 and travel up said racks, thus raising the rear or receiving end of the elevator-frame. The 80 pinions 25, however, being larger than the pinions 26, the forward or distributing end of the elevator-frame is raised with greater rapidity than the rear receiving end, and, if desired, the shaft 24 may be rotated to cause 85 the pinions 25 to engage the racks 22 before the frame is unfolded to cause the cams 41 to engage the stops 40 and throw the pinions 26 in gear with the racks 21, thus giving the forward distributing end of the frame a greater 90 elevation. The object of this feature of my 95 said invention is to raise the front end of the elevator-frame, so that it will be able to distribute upon a high stack, and at the same time raise the lower receiving end, so that the 100 angle of elevation will not be so great, and permit the endless belt to readily carry the straw up the elevator.

I will now describe the mechanism by which the turn-table is operated and the distributing end of the elevator-frame automatically 110 swung back and forward in the arc of a circle.

47 is a circular casting secured to the under side of the arms 11 of the turn-table and concentric therewith. On the under side of said casting are formed circular racks 48 and 49, the teeth of which are oppositely disposed toward each other, the teeth of the rack 48 projecting in toward the center of the turn-table and the teeth of the rack 49 projecting out 115 from the center of said turn-table. Said racks are also concentric with each other and with the turn-table. In the space between said racks and the same distance from each I form on the under side of the casting 47 an annular 120 flange 50.

51 is a cross-bar connecting the transverse bars of the truck or main frame.

52 are bearings formed on the under side of the bar 51 and one of the side bars of the 130 frame. 53 is a shaft mounted in said bearings 52. Said shaft is provided on its outer

end with a crank 54, by means of which it may be operated by hand, and also with a pulley, so that it can be connected with suitable driving-power.

5 55 is a bearing secured to one side of the bar 51.

56 is a short vertical shaft mounted in said bearing and passing up through the hub of the turn-table. 57 is a bevel-gear on the 10 lower end of said vertical shaft, which engages with a bevel-gear 58, mounted on the inner end of the shaft 53.

59 is a pinion, also mounted on the vertical shaft 56 and secured to the bevel-gear 57, or 15 formed integral therewith.

60 is a vertical pindle secured to and projecting down from the cross-bar 51.

61 is a gear mounted on the pindle 60 and engaging with the pinion 59.

20 62 is a pinion, also mounted on the pindle 60, and preferably formed integral with the gear 61.

63 is a short vertical shaft mounted in a bearing 64, attached to the cross-bar 51, and 25 having loosely mounted on its lower portion below the bar 51 a gear 65, which engages with the pinion 62. The short vertical shaft 63 is provided with an eccentric head 66, having a spring-actuating clutch-pin 67, adapted 30 to engage a hole 68 in the face of the gear 65 to connect or disconnect said gear with the shaft 63, so as to throw the turn-table in or out of gear, as hereinafter described. 69 is a pinion rigidly mounted on the upper end of 35 said shaft 63.

70 is a swinging bracket pivoted on the shaft 63 and having a vertical bearing 71 formed in its free end. 72 is a vertical spindle mounted in said bearing.

40 73 is a gear mounted on the upper end of the spindle 72 and engaging with the pinion 69. The bracket 70, having its pivotal point on the shaft 63, the gear 73 and pinion 69 are held in engagement at all positions which the 45 bracket may assume.

74 is a pinion mounted on the spindle 72, above the gear 73, and is either secured to said gear or formed integral therewith. Said pinion 74 engages the circular racks of the 50 turn-table.

75 is a pin or stud projecting above the center of the pinion 74 and engages with the annular flange 50 to hold the pinion in engagement with the racks.

55 76 are recesses or openings formed in the upper side of the circular casting 47.

77 are reversible switch or end blocks, which conform to the shape of and are placed in the openings 76. On one side of said switch-blocks are oppositely-disposed segmental racks 78, the teeth of which are of the same size as the teeth of the circular racks. On the opposite side of the blocks are segmental flanges 79, arranged in the arc of a circle of 65 the same diameter as the annular flange 50. When said blocks are inserted with the racks

down, said racks form a communication or switch connecting the circular racks 48 and 49. When the blocks are inserted with the flanged side down, said flange forms a continuation of the annular flange 50, and does not interfere with the operation of the pinion 70 with the circular racks.

Any desired number of switch-blocks may be used. For convenience I have shown but 75 three in the present drawings. These switch-blocks are intended to regulate the distance the upper discharging end of the elevator-frame will swing, so as to build a large or small stack, and also to transfer the pinion 80 from one circular rack to the other as it reaches the switch-block, thus automatically reversing the swinging movement of the elevator-frame, and causing its discharge end to swing back and forward in a longer or shorter 85 arc, as desired. The operation of this portion of my invention will be readily understood. The switch-blocks are first adjusted to give the turn-table the desired movement, so that the end of the elevator-frame will move in a 90 greater or smaller arc. The pinion 74 will be presumed to be in engagement with the outer rack, as shown in the drawings, as said pinion is operated through the mechanism described, the turn-table moved in one direction 95 until the switch-block reaches the pinion which engages with the rack on the block and is transferred to the inner rack, and the movement of the turn-table and consequent movement of elevator-frame reversed, the pinion being 100 again transferred to the outer rack when it reaches the opposite switch-block.

80 is a horizontal shaft mounted in bearings 81 on the turn-table and having on its inner end a bevel-gear 82, which engages with 105 a bevel-gear 83, mounted on the upper end of the vertical shaft 56. 84 is a pulley mounted on the outer end of said shaft 80.

85 are pulleys mounted on the shaft 17. 86 is a belt connecting said pulleys.

87 are rollers or pulleys, also mounted on the shaft 17, on which the endless carrier-belt 187 is mounted, and by means of which said carrier is operated.

88 are eccentrics secured on opposite ends 115 of the shaft 17. 89 are pitman-arms mounted on said eccentrics and having secured to their outer ends an oscillating receiving and feeder table 90.

91 are braces secured at one end to the lever-arms 18 and having their upper ends pivotally secured to the under side of the table 90. The straw is received upon the table and is moved forward and deposited upon the carrier-belt by the movement of said table.

Having thus fully described my invention, what I claim as new, and desire to secure by Letters Patent, is—

1. In a straw-stacker, the combination, with a turn-table having two parallel lever-arms 130 secured thereto, of an elevator-frame having its lower receiving end pivoted to the other

- ends of said lever-arms, two parallel and upwardly-extending segmental racks secured to the turn-table, two parallel and downwardly-extending racks secured to the elevator-frame, 10 5 a transverse shaft mounted in bearings in the lever-arms and interposed between the oppositely-arranged racks, two sets of pinions mounted on the transverse shaft, one set engaging the upwardly-extending rack and the other set engaging the downwardly-extending rack, and mechanism for rotating said shaft, all constructed, arranged, and operating substantially as shown and described. 15 10 In a straw-stacker, the combination, with a turn-table and the parallel lever-arms 18, pivoted at one end to said table, of the elevator-frame 15, pivoted at its lower receiving end to the other ends of said arms, the upwardly-extending parallel segmental racks 21, secured to said table, the downwardly-extending parallel segmental racks 22, secured to the elevator-frame, the transverse shaft 24, mounted in bearings 23 in the lever-arms, the pinions 25, mounted upon the shaft 24 and engaging with the racks 22, the smaller pinions 26, also mounted upon said shaft and engaging the racks 21, and means for rotating said shaft 24, all constructed, arranged, and operating substantially as shown and described. 20 25 30 35 40 45 50 55 60 65 70 75 80 85 90 95 100 105 110 115 120 125 130 135
3. In a straw-stacker, the combination, with a turn-table and the parallel lever-arms 18, pivoted at one end to said table, of the folding elevator-frame 15, pivoted at its lower receiving end to the other ends of said lever-arms, the upwardly-extending parallel segmental racks 21, secured to said table, the stops 39, located below the racks 21, the projections 40, to one side of and at the lower end of said racks, the downwardly-extending parallel racks 22, secured to the elevator-frame, the transverse shaft 24, mounted in bearings 23 in the lever-arms, the pinions 25, mounted upon the shaft and engaging with the racks 22, the smaller pinions 26, also mounted upon said shaft and adapted to engage the racks 21, the cams 41, mounted upon the transverse shaft and adapted to rest upon the stops 39 when the elevator-frame is in an inoperative position, having shoulders 42, adapted to engage the projections 40 to throw the pinions 26 in gear with the racks 21 when the elevator-frame is in an operative position, and means for rotating the transverse shaft, all constructed, arranged, and operating substantially as shown and described. 4. In a straw-stacker, the combination, with a turn-table and the parallel lever-arms 18, pivoted at one end to said table, of the elevator-frame 15, having its lower receiving end pivoted to the other ends of the lever-arms, the upwardly-extending parallel segmental racks 21, secured to the turn-table, the downwardly-extending parallel segmental racks 22, secured to the elevator-frame, the transverse shaft 24, mounted in bearings 23 in the lever-arms, the pinions 25, mounted upon the shaft 24, engaging the racks 22, the pinions 26, also mounted upon the shaft 24 and engaging the racks 21, the main shaft 36, mounted in bearings on the lever-arms, means for rotating said shaft, a worm-wheel 27, mounted upon the shaft 24, a box or housing inclosing said worm-wheel, the sleeve-bearing 29, projecting from said box or housing and having its end pivotally supported on the main shaft, the short shaft 32, mounted in said sleeve-bearing, the worm 33 on one end of said shaft 32, engaging the worm-wheel, the bevel-gear 34, mounted on the other end of said shaft, and the bevel-gear 37, mounted on said main shaft and engaging the gear 34, all constructed, arranged, and operating substantially as shown and described. 5. In a straw-stacker, the combination, with a truck, of a turn-table suitably mounted thereon and provided on its under side with the concentric circular racks 48 and 49, having oppositely-arranged teeth, the annular guide-flange 50, located between said racks, and the removable and reversible switch-blocks 77, having on one face segmental racks 78, and on their opposite faces the segmental flanges 79, substantially as shown and described, as and for the purpose set forth. 6. In a straw-stacker, the combination, with a truck, a turn-table mounted thereon and provided on its under side with concentric circular racks 48 and 49, an annular flange 50, located between said racks, and the removable and reversible switch-blocks 77, having on one face the segmental flange 79 and on their opposite faces the segmental racks 78, for the purpose set forth, of the swinging bracket 70, pivoted on the truck-frame, the vertical spindle mounted on said bracket, the pinion 74, mounted on said spindle and engaging the circular racks, and provided with a centrally-projecting pin or stud engaging the guide-flange, and mechanism for rotating said pinion 74, all constructed, arranged, and operating substantially as shown and described. 7. In a straw-stacker, the combination, with a truck, a turn-table mounted thereon and provided on its underside with concentric circular racks 48 and 49, an annular guide-flange 50, located between said racks, and the removable and reversible switch-blocks 77, having on one face the segmental racks 78, adapted to form a communication between the racks 48 and 49, and on their opposite faces the segmental flanges 79, adapted when in position to form a continuation of the guide-flange, of the short vertical shaft 63, mounted in bearings on the truck, a gear 65, loosely mounted on the shaft, a spring clutch-pin 67 for rigidly securing the gear to said shaft, mechanism for rotating the gear 65, a pinion 69, rigidly mounted on the upper end of the shaft 63, a swinging bracket 70, pivoted on said shaft 63, a vertical spindle 72,

mounted in said bracket, a gear 73, rigidly mounted on said spindle and engaging with the pinion 69, and a pinion 74, rigidly mounted on said spindle 72 and engaging the circular racks, and provided with a centrally-projecting pin or stud 75, engaging the guiding flange, all constructed, arranged, and operating substantially as shown and described, as and for the purpose set forth.

In testimony whereof I affix my signature in presence of two witnesses.

SAMUEL BUFKIN.
